UNITED STATES PATENT OFFICE.

FRANK M. WELCH AND THEODORE PRESCOTT, OF PILLAGER, MINNESOTA.

HOT-AIR FURNACE.

Application filed May 13, 1922. Serial No. 560,675.

To all whom it may concern:

Be it known that we, FRANK M. WELCH and THEODORE PRESCOTT, citizens of the United States, residing at Pillager, in the county of Cass and State of Minnesota, have invented new and useful Improvements in Hot-Air Furnaces, of which the following is a specification.

One object of our said invention is the provision of a hot air furnace which while simple and inexpensive in construction is possessed of the capacity of heating air for a considerable period of time after the fire has gone out, and is also possessed of the capacity of facilitating the passage of hot air from the furnace with a view to promoting the heating of a building.

To the attainment of the foregoing, the invention consists in the improvement as hereinafter described and definitely claimed.

In the accompanying drawings, forming part of this application:

Figure 1 is a front elevation of the furnace constituting the best practical embodiment of our invention that we have as yet devised.

Figure 2 is a side elevation of the same.

Figure 3 is a vertical cross-section taken in the plane indicated by the line 3—3 of Figure 2.

Figure 4 is a horizontal section taken in the plane indicated by the line 4—4 of Figure 1.

Similar numerals of reference designate corresponding parts in all of the views of the drawings.

In furtherance of our invention the furnace casing 1 is made of considerable thickness of brick or other refractory and insulating material.

The said casing 1 is characterized by upper dead air spaces 2 to increase its insulating capacity, and is also characterized by openings 3 arranged in the base of the side walls of the casing and designed to admit cold air to the interior of the casing. The casing 1 is further characterized by a top wall, the inner side of which is arcuate transversely of the furnace as indicated by 4 for an important purpose hereinafter set forth.

Within the casing 1 is arranged a fire box 5 of cast iron or other appropriate conductive material, to the rear upper portion of which is connected an uptake 6. The said fire box 5 is provided in its forward por-

tion with a grate 7, and in the preferred embodiment of our invention the fire box 5 is superimposed on walls 8 of refractory material between which walls are formed an ash pit 9 and a pit 10, arranged in rear of the ash pit, Figure 4, and designed to be filled with dirt, sand or the like, whereby this dirt or sand will be highly heated by the fire in the grate 7, thereby giving off heat after the fire in the grate has died out.

By particular reference to Figure 4 it will be observed that an air supply pipe 11 leads into the interior of the casing 1 at the back of the casing and near the bottom thereof. The said pipe 11 is joined at 12 to a pipe 13 which is disposed at right angles to the pipe 11 and is designed to be connected at its upper end with the atmosphere outside of a building. At a point in line with the pipe 13 the pipe 11 is provided with an opening 14 which is disposed within the building containing the furnace. At 15 is arranged a valve, pivoted at 16 and provided with a resilient handle 17, opposed to a fixed segmental rack 18. In virtue of this construction it will be observed that the valve 15 can be placed in various positions in the arc indicated by dotted lines and arrows in Figure 4. For instance, when the valve 15 is positioned as shown in Figure 4 air from within the building will be led into the pipe 11 to be supplied to the interior of the casing 1. When the valve 15 is located to close the opening 14 air will be permitted to enter the casing 1 from a point outside the building containing the furnace, while when the valve 15 is positioned against the side of the pipe 13 air from the opening 14 and also from the pipe 13 will be permitted to enter the casing 1. From this it follows that the person in charge of the furnace can regulate the air supply to the casing 1 according to the weather conditions that prevail.

At 19 and 20 are face plates appropriately fixed to the front wall 21 of the casing 1, it being understood in this connection that the front wall 21 and the back wall 22 of the casing 1 are formed of appropriate non-conducting material such as brick. The face plate 19 carries a fire door 23 on which is arranged by preference a damper 24, and the face plate 20 carries the ash door 25, equipped with a damper 26. These features, however, are not of the essence of our in-

vention and need not, therefore, be further described.

Leading at different points from the arcuate top of the interior of the casing 1 are 5 hot air pipes 27 which according to our invention are disposed radially with respect to the circle described in part by the said transverse arcuate wall 4. This arrangement of the pipes 27 is materially advantageous 10 inasmuch as it conduces to the free passage of hot air from the interior of the casing 1 to the apartments that are to be heated by the hot air supplied through the said pipes 27, and in view of the arcuate 15 wall, the hot air pipes 27 are located in a position substantially vertically above the fire box for evenly distributing the heated air from the fire box to the different pipes.

It will be readily apparent from the foregoing 20 that due to the insulating quality of the casing 1, air entering and passing through the casing will be heated to an appreciable extent for a considerable period of time after the fire in the fire box 5 has gone 25 out. It will also be appreciated owing to the insulating quality of the casing 1 and the arrangement of the pipes for supplying air to the interior of the casing 1 and the pipes for conducting hot air from the casing 30 1, a small fire in the fire box 5 will suffice to adequately heat the apartments in connection with the pipes 27 of which any reasonable number may be employed in proportion to the size of the furnace as a whole.

We have entered into a detailed description 35 of the construction and relative arrangement of the parts embraced in the present and preferred embodiment of our invention in order to impart a full, clear and exact understanding of the said embodiment. We do not desire, however, to be understood as confining ourselves to the said specific construction and relative arrangement of parts inasmuch as in the future 40 practice of the invention various changes and modifications may be made such as fall within the scope of our invention as defined in our appended claim.

Having described our invention, what we claim and desire to secure by Letters-Patent, 50 is:

In a hot air furnace, the combination of a casing, means to conduct hot air from the top of the interior of said casing, means to supply air to be heated to the interior thereof, and a fire box located in the casing and spaced from the side and back walls thereof and having a grate in its forward portion and also having a pit adapted to be filled with dirt or sand in its rear portion, whereby 55 this dirt or sand will be highly heated by the fire in the fire box, thereby giving off 60 this heat when the fire in the box has died out.

In testimony whereof, we affix our signatures:

FRANK M. WELCH.

THEODORE PRESCOTT.
